(57) **CLAIM**

The ornamental design for a display screen with graphical user interface, as shown and described.

DESCRIPTION

The FIGURE is a front view of a display screen with graphical user interface.

The outer dashed broken lines in the FIGURE show a display screen or portion thereof, and form no part of the claimed design.

The other dashed broken lines in the FIGURE show portions of the graphical user interface that form no part of the claimed design.

The stippled shading in the FIGURE indicates a contrast in appearance.
